Primary Examiner — Dana Meyrow

(74) Attorney, Agent, or Firm — Greenblum & Bernstein,
P.L.C.(57) **CLAIM**

The ornamental design for a packaging bottle, as shown and described.

DESCRIPTION

FIG. 1 is a top, front, right side perspective view of a packaging bottle, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is an enlarged cross-sectional view of the packaging bottle taken along section line 8-8 of FIG. 2 showing only the cut surface.

The shade lines in the Figures show contour and not surface ornamentation. The article of this design is transparent entirely except for the cap, the label covering the neck portion, and the label attached to the body portion. The oblique line shading in the Figures show the transparent portions of the packaging bottle.

The broken lines shown in the drawings illustrate portions of the packaging bottle that form no part of the claimed design.
